UNITED STATES PATENT OFFICE

2,627,898

CHAIR HAVING AN ADJUSTABLE SEAT AND
BACK REST

George McStay Jackson, Chicago, Ill.

Application February 19, 1951, Serial No. 211,714

3 Claims. (Cl. 155—116)

1

This invention relates to certain new and useful improvements in a chair having an adjustable seat and back rest in which the seat and back are simultaneously movable to permit adjustment of the same to a desired predetermined position most comfortable to the occupant. As such the invention has for its principal object the provision of an arrangement for accomplishing the adjustment of the seat and back of the chair relative to the side frames thereof upon pressing engagement of the back of the occupant with the seat and back of the chair.

Another object of this invention is to provide an article of furniture of this character by which the seat and back of the chair may be adjusted by the person sitting in the chair, to positions which will be most comfortable.

Yet another and equally important object of the invention is the provision of an arrangement for accomplishing the foregoing objects, which will be economical in manufacture.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a side elevational view of the chair embodying my invention;

Fig. 2 is a side elevational view similar to Fig. 1, but showing the parts thereof in different positions;

Fig. 3 is a perspective exploded view of the several parts comprising my improved chair;

Fig. 4 is a sectional detail view taken substantially on line 4—4 of Fig. 5;

Fig. 5 is a front view of the chair;

Fig. 6 is a sectional detail view taken on line 6—6 of Fig. 5.

The preferred form of construction of my improved chair is illustrated in the drawings. In this connection, my improved chair comprises a structure including side frames 10 arranged in parallel spaced relation and interconnected together by a structure 10' comprising front and rear crossbars 11 and 12. A back rest 14 of suitable construction is pivotally connected as at 15 to the frames 10.

The chair further includes a seat 16 of suitable construction including a seat cushion 17 and a bottom plate 18. The back rest 14 likewise includes a cushion 19 and a back plate 20. These cushions may be of any approved construction which will afford the maximum comfort to the user of the chair.

2

Extending between the crossbars 11 and 12, and in parallel spaced relation with respect to each other, are mounting bars 21. Secured to the bottom of the seat 16 in any suitable manner and mounted in spaced relation with respect to each other, are two horizontal seat supporting bars 22 and 22'. These supporting bars have in their bottom portions a pair of corresponding U-shaped grooves 23 and 23', which are adapted to receive the mounting bars 21. These channel-shaped grooves 23 and 23' are of such a depth that ball bearings 24 may be inserted in the channels so as to ride upon the top of the mounting bars 21, and still form a flush surface with the bottom of the bars, as shown in Fig. 6.

The seat supporting bars 22 and 22' with their corresponding ball bearings 24 in the channel-shaped grooves 23 and 23' are secured to the mounting bars 21 by means of securing plates 25. After the seat 16 with its horizontal bars 22 and 22' secured to the bottom thereof, is placed upon the mounting bars 21, the plate 25 is placed across the bottom and in parallel relation with the supporting bars 22 and 22', and secured thereto in any suitable manner, thus providing the seat 16 with movable connection to the frame 10 of the chair.

The mounting bars 21 have coil springs 26 threaded on their forward end, such that the spring will engage the front crossbar 12 and the forward seat supporting bar 22, to yieldably hold the seat in normal position with respect to the frame 10. Also located in the mounting bars 21, but near the rear crossbar 11, is a stop pin 27, which is adapted to engage the rear seat supporting bar 22' to prevent further movement of the seat in a rearward direction.

Secured to the back plate 20 as at 28 is one end portion of a depending arm 29. The free end portion of this arm 29 has at its lower end an elongated slot 30 formed therein. This slot 30 is adapted to receive a screw 31 threaded into the seat 16 as at 32, and disposed between the screw head 33 and the arm 29 is a coil spring 34. By this arrangement, when the seat is forced forward, the back will pivot on the connections 15, and the arm 29 will move against the action of the spring 34, as shown in Fig. 2.

The arrangement is such that a person sitting on the seat 16 with his back against the back rest 14, may adjust the back rest 14 and the seat 16 to such positions as will be most comfortable to him. This is accomplished by simultaneously adjusting the back rest 14 and seat 16 relative to the frames 10 by bearing the body against the

seat 16 and back rest 14 in the direction in which the occupant desires to move them, so as to arrange them in a position best suited to his comfort.

When the weight of the occupant is removed from the seat 16 and the back rest 14, the springs 26 are of sufficient strength to cause these parts to assume their normal initial position, such as shown in Fig. 1.

My improved chair has many uses. It may be used for home purposes, in offices, theaters, and many other places. The construction comprises relatively few parts and is highly economical both in manufacture and use.

While I have illustrated and described this preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. An article of furniture comprising a structure including a pair of interconnected parallelly arranged side frames, a back rest arranged between said frames, means pivotally connecting the back rest to said frames for pivotal movement relative to said frames by the weight of a body thereagainst, a seat arranged between the frames below and forwardly of the back rest, means providing a slidable connection between the seat and said structure whereby said seat may move inwardly and outwardly relative to said frames, said last named means comprising a pair of seat supporting bars having U-shaped grooves, roller members movable in said grooves and engaging an element of said structure, said bars having connection with the seat and slidable connection with said element of structure, spring means for resisting outward movement of said seat, an arm fixed to and depending from said back rest, and means pivotally connecting the free end of the arm to the back of said seat.

2. An article of furniture comprising a structure including a pair of interconnected parallelly arranged side frames, a pair of mounting bars disposed between and parallel to said side frames, a back rest arranged between said frames, means pivotally connecting the back rest to said frames for pivotal movement relative to said frames by the weight of a body thereagainst, a seat arranged

between the frames below and forwardly of the back rest, means providing slidable connection between the seat and said structure whereby said seat may move outwardly relative to said frames, said last-named means comprising a pair of seat supporting bars having U-shaped grooves, roller members movable in said grooves and engaging said mounting bars, said seat supporting bars having connection with the seat and slidable connection with said mounting bars, spring means for resisting outward movement of said seat, stop means on said mounting bars to retain said seat in normal position as against said spring action, and a connection between the back rest and the seat whereby said seat will be moved against the action of said spring means by pivotal movement of the back rest relative to the frames by the weight of said body thereagainst.

3. An article of furniture comprising a structure including a pair of interconnected parallelly arranged side frames, a pair of mounting bars disposed between and parallel to said frames, a back rest arranged between said frames, means pivotally connecting the back rest to said frames, a seat arranged between the frames and forwardly of the back rest, means providing slidable connection between the seat and said structure, said last-named means comprising seat supporting bars connected to the seat in spaced parallel relation with respect to each other and substantially at right angles with respect to the mounting bars, said seat supporting bars having grooves formed therein and said mounting bars engaging in said grooves, spring elements embracing the mounting bars and disposed thereon between one of said seat supporting bars and an element of said structure, an arm fixed to and depending from said back rest, and means pivotally connecting the free end of the arm to the back of said seat.

GEORGE McSTAY JACKSON.
